HAND STAMPING STENCIL HOLDER

James R. Thomas, Deerfield, Ill., assignor to
Joseph A. Weber, Mount Prospect, Ill.

Application April 28, 1952, Serial No. 284,779

3 Claims. (Cl. 101—125)

1

This invention relates to a new and improved hand stamping stencil holder.

In the shipping of packages from a shipping department of manufacturing companies wherein there are numerous packages constituting a single order which is being directed to a single customer, it is desirable to prepare and make a stencil which includes the name and address of the consignee or purchaser. Such a stencil is preferably of the type employed in duplicating processes and is impressed on each of the packages comprising the single order or at least all of the packages and parcels which are to be sent to the one customer. The packages may have irregular surfaces and invariably do. Thus with ordinary stencils or hand stamping devices, it is extremely difficult to obtain a legible reproduction of the stencil on each of the packages.

It is therefore a principal object of the present invention to provide a hand stamping stencil holder which will cause an even and uniform impression on irregular surfaces.

An important object of this invention is the provision of means in a stencil holder wherein the stencil is loosely held without binding and may be easily replaced by other stencils.

Another important object of this invention is to supply a stencil holder having a relatively deep yieldable pressure pad under the stencil held therein for the purpose of accommodating relatively irregular and rough surfaces.

Another and further important object of this invention is to provide a hand stamping stencil holder in which the parts are relatively easily removable and wherein the pressure pad consists of a very soft and pliable sponge synthetic rubber pad held in centered position by means of an endless band of inked cloth without the aid of cements or adhesives which would cause binding or distortion of the pad and wherein the stencil is loosely held over the soft pressure pad.

Another and still further important object of this invention is to supply a hand stamping stencil holder with relatively widely spaced inwardly and downwardly turned flange means for removably receiving a stencil and having an inked pressure pad located centrally between the wide spaced flanges and adapted to exert a uniform pressure against the stencil held by the wide spaced flanges.

A still further important object of this invention is to provide a hand stamping stencil holder with the several parts thereof quickly disassembled and readily put together with a single screw means to hold the entire unit in rigid assembled relationship.

Other and further important objects will become apparent from the disclosures in the following specification and accompanying drawings.

In the drawings:

2

Fig. 1 is an end view of the hand stamping stencil holder of this invention.

Fig. 2 is a top plan view of the device as shown in Fig. 1 with the stencil removed.

5 Fig. 3 is a sectional view taken on the line 3—3 of Fig. 2.

As shown in the drawings:

The reference numeral 10 indicates generally a frame or support upon which the stencil holder of this invention is built. A handle 11 in the form of a hand gripping knob is provided with a downwardly extending screw 39 in substantially the center thereof for engagement with the frame member 10.

15 The frame 10 includes a relatively flat back portion 12 flanked by downwardly and outwardly bent portions 13 and 14. Each of the inclined portions 13 and 14 is further provided with inwardly and downwardly bent flanges 15 and 16 respectively. These inwardly and downwardly inclined flanges 15 and 16 are relatively widely spaced apart with their inner edges disposed parallel one to the other. It is the inwardly and downwardly inclined flanges 15 and 16 directed

20 toward each other which comprise the means for loosely holding a stencil in the stamping device of this invention. The frame 10 may then be said to constitute a stencil holding frame. The stencil indicated by the numeral 17 is shown

25 in Fig. 1 wherein one edge 18 projects over the inclined flange 15 and within the V-shaped notch formed by the adjoining flange portions 13 and 15 of the stencil holding frame 10. The opposite and parallel disposed edge 19 of the stencil 17 is positioned over the lip or flange 16 on the opposite side of the stencil holding frame 10 and is positioned within the V-shaped notch formed by the adjoining flange portions 14 and 16 of the frame 10. The stencil 17 is made of relatively resilient paper stock material and the slight bending of the opposite edge portions 18 and 19 for nestling within the V-shaped notches in the holder frame 10 causes the stencil to be held sufficiently for the imprinting of the material from the stencil.

30 Intermediate the stencil holding flanges there is provided a channel or U-shaped bracket 20 made preferably of metal such as steel. The channel shaped bracket 20 includes a perforated bottom 21 and upwardly extending spaced apart perforated side walls 22 and 23. The upper ends of these parallel side walls 22 and 23 are spaced slightly apart from and closely positioned adjacent the underside of the relatively flat portion 12 of the stencil holding frame 10. A metal strip 24 is provided with a central flat portion 25 across the top thereof, and the end portions 26 and 27 are bent downwardly to an inclined position. The metal strip 24 bent as described is adapted to fit within the channel 20, and by means of oppositely disposed welds 28 and 29,

the metal strip 24 is rigidly secured to the metal U-shaped channel 20. The extremities of the bent portions 26 and 27 of the strip 24 are coextensive with the ends of the channel 20. The weld 28 thus joins the end portion 26 of the strip 24 to the perforated base 21 along their adjoining edges, and similarly the weld 29 joins the bent portion 27 of the strip 24 to the end of the base 21 of the channel 20.

As best shown in Fig. 3, the handle 11 is equipped with the downwardly extending threaded stud 30 which passes loosely through an aperture 31 in the stencil holding frame 10 and thereupon threadedly engages an aperture 32 in the flat portion 25 of the metal strip 24. Thus as the handle 11 is screwed downwardly, the threaded stud 30 draws the channel and its integral metal strip 24 up against the underside of the flat portion 12 of the stencil holding frame 10.

Beneath the perforated channel 20 is positioned a felt pad 33 and beneath the pad 33 is a very soft and pliable sponge synthetic rubber thick pad 34. There is no adhesive or cement means for holding the pad 33 to the channel 20 nor is there any cement or adhesive means holding the sponge rubber pad 34 to the felt pad 33.

An endless piece of cloth material 35 is provided with dowel pins, preferably wooden, 36 and 37 inserted through the outer ends thereof. The one cloth-covered dowel pin 36 is placed within the channel 20 over the side wall 22 and thence around and beneath the felt and rubber pads 33 and 34 and thereupon up the other side over the side wall 23 of the channel 20 and the dowel pin 37 turned over and lying within the channel 20. The cloth 35 is applied to the channel 20 and the pressure pads 33 and 34 when the channel is removed from the stencil holding frame 10. Thereafter the handle 11 is screwed onto the channel 20 and its unitary metal strip 24 causing the assembly of parts as previously described. The close proximity of the upper ends of the channel walls 22 and 23 to the underside of the frame 10 prevents the withdrawal of the cloth-holding dowel rods 36 and 37 when the device is drawn tightly together by a screwing of the handle 11 downwardly. It should be understood that the diameter of the rods 36 and 37 is greater than the space between the upper ends of the walls 22 and 23 and the underside of the frame 10.

The cloth 35 in addition to holding the yieldable pressure pads in proper non-binding position beneath the perforated channel 20 also carries an ink to be imparted to the stencil 17 to effect an imprinting thereof when the stamp is urged downwardly by an operator. The ink may and does fill the porous pads 33 and 34 as a reservoir so the stencil may be used for many imprints without reinking the device. The perforated channel 20 permits the ink free and uninterrupted passage therethrough so there are no undesirable effects of expansion or contraction of the ink caused by making an impression of the stencil.

In the operation of the hand stamping stencil holder of this invention, the device is assembled as previously described with the cloth holding the yieldable pressure pads in aligned position beneath the channel 20. A stencil to be imprinted has one side thereof inserted in the V-slot 13-15 of the holding frame 10 and the opposite side is inserted in the V-slot 14-16 of frame 10. The operator now presses the entire unit down against a surface to be imprinted, and any irregularities in that surface will be compensated for by the 75

deep sponge rubber pad 34. The omission of cements or adhesives in the assembly of the pressure pads eliminates distortion of the pads and thus an even and uniform impression is made possible. Disassembly and replacement of any of the parts is relatively easy by reason of the unscrewing of the handle 11. Further, the stencils to be imprinted are not clamped to the device and thus they are free to align themselves over and around the ink and pressure means of the stamp. Many impressions may be made with a single stencil and thereafter the stencil may be easily removed and another inserted.

Various details of construction may be changed throughout a wide range without departing from the principles disclosed herein, and I therefore do not propose limiting the patent granted hereon otherwise than as necessitated by the appended claims.

What is claimed is:

1. A hand stamping stencil holder comprising a frame, a handle mounted on said frame, spaced apart parallel flange means formed on said frame for loosely engaging the side edges of a stencil, and an inked pressure pad means carried on said frame between said spaced apart flange means whereby when the stencil holder is pressed against a surface the inked pressure pad causes an imprinting of the material on the loosely held stencil, said inked pressure pad means includes a perforate metal channel member opening upwardly within said frame, a strip of metal narrower than said channel member and positioned centrally therein and fixedly fastened thereto, said strip of metal defining longitudinally extending spaces along the marginal edges thereof to the channel member sides, means on said handle engaging and holding together the frame and the channel member, yieldable ink holding means positioned on the underside of said channel, means holding said yieldable means to said channel, said last named means including a generally rectangular piece of cloth having a rod journally carried in opposed parallel edges thereof, said piece of cloth surrounding said yieldable ink holding means and extending upwardly over the sides of said channel and the rod edges of said piece of cloth disposed within said longitudinally extending spaces, whereby when said handle is in frame and channel holding position the cloth piece is similarly locked in position and when the handle is removed the cloth piece may be removed.

2. A device as set forth in claim 1 in which the yieldable ink holding means includes a felt pad and a soft pliable synthetic rubber sponge pad.

3. A device as set forth in claim 1 in which said rods have a diameter greater than the spacing between the tops of the sides of the perforate channel and said frame, whereby the cloth fixedly holds the yieldable means to the perforate channel.

JAMES R. THOMAS.
